UNITED STATES PATENT OFFICE.

LOUIS V. ARONSON, OF NEWARK, NEW JERSEY.

TOP.

Application filed March 28, 1927. Serial No. 178,933.

The invention relates to tops and has as an object the provision of a top having means for spinning the same permanently associated therewith.

It is a further object of the invention to provide a top having means operated by its spinning action to cause illumination thereof.

It is a further object of the invention to provide a top having a base upon which the top may spin and carrying one element of the illuminating means, and means to prevent the base and the illuminating means from turning.

It is a further object of the invention to improve the structure of tops.

Further objects of the invention will appear from the following description when read in connection with the accompanying drawing showing an illustrative embodiment of the invention, and wherein:

Figure 1 is a plan view.

Figure 2 is a central vertical section.

Figure 3 is a detail plan view of the illuminating means.

Figures 4 and 5 are detail sections on the corresponding lines of Fig. 2, and

Figure 6 is a perspective view of a portion of the illuminating means and the stationary base.

As shown, the device comprises a revoluble body 10, a base 11 and means 12 to spin the top. The body 10 is shown as comprising a shell having a lower member 13 and an upper member 14 separably united as at 15.

The separable means of the top are shown as comprising an annular shoulder 16 carried by the shell 13, and lugs 17 bent in from the rim 18 of the shell 14 overlapping the vertical portion 19 of the shell 13, which lugs may be entered through notches 20 in the portion 19 and the shoulder 16 when the shell 14 may be revolved to bring the lugs 17 under the shoulder 16 to provide a bayonet type connection between the shells.

It will be obvious that the entire rim 18 might be spun under the shoulder 16 if it is desired to permanently secure the shells together.

To spin the top there is shown a central rod 21 revolvably associated with the shell 14, and passing through a sleeve 22 carried by the shell. To set the sleeve 22 into revolution there is shown a ratchet wheel 23 rigidly carried by the sleeve 22 and a pawl 24 in

contact with the ratchet teeth 23. The pawl 24 may be pressed into contact with the ratchet wheel 23 by centrifugal action under the influence of a momentum member 24', forming a bell crank with the pawl, which pawl is carried by an element 25 of a drum 26, about which is normally coiled a flexible member 27 projecting through an opening 28 in a housing 29, the housing 29 having an upwardly projecting cylindrical portion 30 in which the rod 21 is journaled and in which it is rigidly fixed, whereby the housing 29 and the cylindrical portion 30 may be held stationary while the drum 26 is caused to revolve by pulling upon the flexible member 27. To cause the return to normal of the flexible member 27, there is shown a coiled spring 31 anchored as at 32 to the drum, and anchored at its opposite end, as at 33, to the member 30.

A ball 34 is shown applied to the end of the flexible member 27 to prevent the same being drawn to the interior of the housing 29, and to afford a grasp for manipulation.

To cause illumination of the top, during its spinning action, there is shown an annular abradant member 35 carried by the shell 13 and rigid therewith, and pyrophoric element holding means illustrated in detail in Fig. 6. As there shown, the means for holding the pyrophoric element is shown as mounted upon a sleeve 36, rigidly connected to the base 11, being disk 37 rigidly mounted upon the sleeve 36. The disk 37 is shown as formed with wings 38, 39, having downturned ears 40, in which are journaled movable members 41, 42 carrying the pyrophoric elements 43, 44. To clamp the elements 43, 44 in position, there are shown eccentrics 45, 46, each having a lever 47, 48 projecting therefrom by which the elements may be unclamped, renewed or adjusted, and again fixed in position.

The members 41, 42 are adapted to drop by gravity so as to bring the elements 43, 44 into contact with the abradant surfaced member 35, and are prevented from rising out of position by means of fingers 49, 50 projecting beneath the disk 37. The disk 37 may be held in its lowermost position by means of a spring 51 abutting against the disk and against the portion 52, housed within the shell 14 and rigid therewith. The portion 52 is shown as connected with the shell by means of a frusto-conical portion 110

53 having lugs 54 passing through perforations in the shell and bent into engagement therewith.

5 *Operation.*

The top is held in an upright position by grasping the member 30 with the base 11 in contact with a spinning surface, the pin 21 resting against the surface. The flexible member 27 is pulled upon, causing revolution of the drum 26 when by centrifugal action the pawl 24 will be thrown into engagement with the teeth 23, causing revolution of the shell. When the member 27 is slacked the spring 31 will rewind the same, and by successive pulls upon the member a rapid motion of the top may be produced. The base 11 by engagement of the teeth 55 with the spinning surface will be prevented from revolution, thereby holding the pyrophoric elements stationary and in contact with the spinning abradant member, thereby providing a shower of sparks within the shell.

To permit emission of the light of the sparks the shell is shown as provided with a plurality of perforations 56. To cause a display of colors there are provided a plurality of colored transparent or translucent elements 57 underlying the perforations and secured to the interior of shell 14.

Minor changes in the physical embodiment of the invention may be made within the scope of the appended claims without departing from the spirit of the invention.

35 I claim:

1. A top comprising, in combination, a central pin, a shell revolubly mounted on said pin, ratchet teeth carried by said shell, actuating mechanism carried by said pin 40 comprising means revoluble on said pin, a pawl carried by said means, means to cause revolution of said revoluble means alternating in opposite directions, means to press said pawl into engagement with said ratchet teeth in one direction of movement of said revoluble means and to allow said pawl to slip over the teeth in the opposite direction of movement thereof, and a housing means

carried by said pin to be grasped by the user to hold the pin stationary while the shell 50 is set into motion.

2. A top comprising, in combination, a central pin, a shell revolubly mounted on said pin, ratchet teeth carried by said shell, a housing having a portion adapted to be 55 grasped by a user and rigidly carried by said pin, a drum in said housing revoluble on said pin, a flexible member normally wound on said drum, attached thereto, and projecting through said housing, resilient 60 means to rewind said flexible member when unwound from said drum by pull on said projecting portion, a pawl carried by said drum, and means to press said pawl into engagement with said teeth during unwind- 65 ing movement of said member.

3. A top comprising, in combination, a central pin, a shell revolubly mounted on said pin and retained thereon, means carried by the pin to cause revolution of the shell, 70 a sleeve projecting within the shell revolubly associated with said pin, a base carried by said sleeve and surrounding said pin, said pin and base adapted to bear on a supporting surface, means carried by said base acting to 75 hold said sleeve stationary during spinning of the shell, illuminating means within the shell comprising relatively rotatable members one of said members carried by the shell and the other carried by said sleeve and said 80 shell having light emitting openings.

4. A spinning toy comprising, in combination, a shell having light emitting openings, mechanism to cause revolution of the shell, an element revolubly associated 85 with said shell, pyrophoric sparking means associated with said element and shell comprising an abradant surface carried by one of said members and a pyrophoric element holding means carried by the other thereof 90 said holding means comprising a socket for the pyrophoric element and an eccentric pivoted adjacent the socket and adapted to be rotated to clamp the element in adjusted position.

LOUIS V. ARONSON.
